UNITED STATES PATENT OFFICE.

JOSEPH A. LYNCH, OF LEONIA, NEW JERSEY, ASSIGNOR OF ONE-HALF TO MARTIN J. CUMMINS, OF FORT LEE, NEW JERSEY.

WALL STRUCTURE.

Application filed December 6, 1922. Serial No. 605,312.

To all whom it may concern:

Be it known that I, JOSEPH A. LYNCH, a citizen of the United States, and a resident of Leonia, in the county of Bergen and State of New Jersey, have invented a new and Improved Wall Structure, of which the following is a full, clear, and exact description.

The present invention relates to new and useful improvements in wall constructions, and it pertains more particularly to a wall construction formed of brick of the ordinary type combined with a special form of building block.

It is one of the primary objects of the invention to construct the wall so that between its inner and outer surfaces there will be provided air spaces for the circulation of air through the wall for the purpose of eliminating moisture.

It is a further object of the invention to construct a building block so that it may be used in combination with bricks of conventional size, in the building of a wall.

With the above and other objects in view, reference is had to the accompanying drawings, in which—

Figure 1 is a perspective view partly in section, of a wall constructed in accordance with the present invention;

Fig. 2 is a detail perspective view of a slightly modified form of block.

Referring more particularly to the drawings, the wall comprises an outer section formed of bricks of conventional type, and an inner section formed of building blocks of special construction, the building blocks being so formed as to provide means whereby they may be interlocked with the bricks forming the outer section, thus providing a wall consisting of interlocked outer and inner sections. The building blocks are further formed in such a manner that when the wall is completed there will be air chambers formed extending longitudinally of the wall in a horizontal plane, and these chambers will communicate with one another by means of openings which extend from one air chamber to the next adjacent chamber.

The reference character 10 designates bricks of conventional form from which the outer section of the wall is formed, and the reference character 11 designates the building blocks used in combination with the bricks to form the wall.

Each of the building blocks 11 comprises

a body portion 12 formed with a curved face 13, said curved face being formed in such a manner as to provide two flanges 14 and 15. The flange 15 has a thickness substantially equal to the thickness of a brick of conventional form, and each of the flanges 14 and 15 is provided with an opening 16. The bottom face of the flange 15 extends throughout the width of the building block 10, while the outer face of the flange 14 terminates at a point designated by the reference character 17 to provide a flange 18. This flange 18 is of a thickness equivalent to the thickness of a brick and is so arranged with respect to the building block that when a brick is rested upon the outer face 19 of the flange 14, the top face of the brick will occupy a position flush with the top face 20 of the flange 18. The height of the building block 10, that is, the distance from the outer face of the flange 15 to the face 20 of the flange 18, is equivalent to six courses of the bricks 10, the sixth course of bricks resting upon the outer face 19 of the flange 14 of each building block, as shown.

In constructing the wall, the bricks 10 are laid in the ordinary manner; that is, end to end, until five courses have been laid. The sixth course is then laid side to side, as shown, by which method the bricks laid side to side will bring the brick section of the wall up to a plane flush with the top face 19 of the building blocks of the second course after the latter course is finished. When this second course of building blocks is positioned, a course of bricks is laid edge to edge and the bricks thus laid will extend over and occupy a position on top of the face 19 of the flange 14 of the second course of building blocks.

The wall is constructed in the above manner, and it will be noted that as each course of building blocks is laid, the lower flanges 15 thereof will rest upon those bricks laid edge to edge which rest upon the flange 14 of the building blocks in the next lower course. By this construction, after the brick section and the building block have been completed, the curved face of the building blocks will provide horizontally extending air spaces, and communication between these spaces is had through the medium of the openings 16 in the flanges 14 and 15 of the building blocks, it being understood that at this portion of the building blocks, half

bricks, such as designated by the reference character 25, are employed, in order not to close the openings 16 in the flanges 14 and 15.

In that form of the building block shown in Fig. 2, air spaces 26 are employed for the purpose of tightening the construction of the blocks. In other respects, however, the block is similar to that shown in the preferred form of the invention.

From the foregoing it is apparent that the present invention provides means whereby a wall may be formed of interlocking sections of masonry in the form of laid bricks and building blocks, the wall having the external appearance of a brick wall and possessing all of the advantages of a wall constructed of building blocks, such as ventilation for the purpose of reducing to a minimum the disadvantages of moisture, and a finished interior surface for the reception of plaster, a finishing coat, or the like, 27.

What is claimed is:

1. In a wall structure, an outer brick section and an inner block section, the blocks of said inner block section being provided with a curved face positioned adjacent the outer brick section to provide continuous air chambers between the brick section of the wall and the block section thereof.

2. A building block for wall construction, comprising a main body portion of substantially rectangular form and having an arcuate face arranged to provide two flanges spaced with relation to each other, and a shoulder formed on one of said flanges, said shoulder being of a thickness equal to the thickness of a conventional brick, as and for the purpose set forth.

3. A block for walls comprising a main body portion of substantially rectangular form and having a curved face providing a pair of spaced parallel flanges, each of which flanges is provided with a cut-out portion, and a shoulder formed on one of said flanges and occupying a position at right angles thereto.

4. A building block adapted for use with brick facings, said block being formed with a recessed portion intercepted by cutout portions whereby continuous air passages at substantially right angles to each other are provided.

5. A building block adapted for use with brick facings and adapted for interlocking engagement therewith; said block having intersecting recessed portions whereby intersecting ventilating air passages are provided.

6. A building block for use with brick facings and adapted for interlocking engagement therewith, said block having spaced flanges, one of which is offset from its respective end of the block a distance equal to the thickness of a conventional brick.

7. A building block comprising a body portion having spaced flanges to provide an intervening space whereby upon combining a plurality of said blocks a continuous air passage in one direction is provided, and cut-out portions formed in said flanges to provide a continuous passage intercepting said first-mentioned air passage when a plurality of said blocks are combined.

JOSEPH A. LYNCH.
